MOVABLE HEARTH MUFFLE FURNACE

Frederick W. Hornbruch, Roselle Park, and Frederick C. Schaefer, Westfield, N. J., assignors to American Gas Furnace Company, Elizabeth, N. J., a corporation of New Jersey

Application January 10, 1951, Serial No. 205,254

1 Claim. (Cl. 263—6)

1

The present invention relates to heat treating machines more especially metal treating furnaces and is concerned with improved means for the continuous feeding of workpieces through the heating zone while maintaining the work enveloped in a protecting or processing atmosphere.

To protect or process work during the heat treating process it has been the common practice to transport the work on a conveyor through a muffle, and in some cases, to vibrate the muffle in such a way as to cause the work to be propelled along its surface. The prior devices were, however, somewhat complicated and involved numerous elements to assemble and maintain in good order, and, in the case of the reciprocable muffle type of furnace, necessitated moving the entire heavy muffle including its attached delivery chute and associated oil cascade mechanism, with the result that considerable power was required to operate the machine to feed relatively small workpieces. The present invention undertakes to construct a heat treating machine in which the massive muffle, its delivery chute and cascade mechanisms, thermocouples, treating gas supply tubes and accessory equipment, remain fixed and immovable, and to provide within the muffle, a movable hearth along which the workpieces are caused to travel from a loading station exteriorly of the furnace, through the tunnel-like muffle, to the delivery chute and quench tank at the exit of the muffle.

In carrying out the aims of the invention we propose to mount a tubular muffle in a normally fixed position within the heating chamber of a furnace, and to incorporate within the muffle a relatively movable hearth. The movable hearth member is fashioned with relatively shallow sides, is open at its delivery end, and extends forwardly beyond the forward open end of the stationary muffle. The extending portion of the hearth slab forms a receiving tray for the work that is to be fed through the muffle. Suitable means are provided, hereinafter to be explained, to effect reciprocatory movement of the hearth slab within the muffle, slowly in one direction and relatively rapidly in the other with an abrupt stop at the end of the latter movement, so that work to be treated is advanced step-by-step along the slab from the receiving end to the delivery end.

Other objects and advantages will be in part indicated in the following description and in part rendered apparent therefrom in connection with the annexed drawings.

2

To enable others skilled in the art so fully to apprehend the underlying features hereof that they may embody the same in various ways contemplated by this invention, drawings depicting a preferred typical construction have been annexed as a part of this disclosure and, in such drawings, like characters of reference denote corresponding parts throughout all the views, of which:

10 Figure 1 of the drawings is a side elevation, partly in section, of a treating furnace embodying the invention.

Fig. 2 is a transverse sectional view taken along line 2—2 of Fig. 1.

15 Fig. 3 is a transverse sectional view of the muffle and hearth on an enlarged scale more clearly to illustrate a preferred construction.

Fig. 4 is a longitudinal view, partly in section, of the muffle and hearth.

20 In the embodiment illustrated, the furnace per se is of the usual construction and comprises a main frame 10, that supports the brick-work 11 which in turn defines and encloses the elongated heating chamber 12. A series of burners 13 located in the walls of the furnace are provided to heat the chamber 12. Pyrometer openings and peep openings are also provided as will be understood.

25 On the floor of the heating chamber spaced supports, e. g. fire-brick blocks 14 are placed in pairs, and across each pair is placed a heat resisting rod or tube 15. The rods extend transversely of the furnace chamber and support at their medial regions, a heat resisting muffle member 16. In the instant embodiment muffle 16 is generally tubular having flat upper, lower, and side walls, is open at its forward end 16a and extends a short distance from the front wall of the furnace chamber. Other muffle shapes may of course be used. The rear end of the muffle is closed, except for treating gas tube 17, and an observation tube 18, and is formed with an opening in its lower wall that communicates with a delivery chute 19. Chute 19 carries a quenching cascade mechanism 20 and leads to a quench tank 21 indicated in dotted lines. The chute 19 extends downwardly through an enlarged opening 22 in the lower wall of the furnace, which opening is normally maintained closed to the entrance or escape of gases by a flange piece 23 carried by the chute. With this construction, the muffle, while normally stationary, is free to stretch or contract with changes in temperature. Such movements being unrestrained by virtue of the roller-like action of

the horizontal bars 15 between the flat underside of the muffle and the flat tops of the supports 14.

The forward end of the muffle is anchored to the front of the furnace by means of bolts 24 that connect with a furnace mounted flange 25 and a muffle mounted flange 26. Compression springs 27 encircle the bolts and react against the respective flanges to keep the forward end of the muffle in a normally fixed but yieldable position relative to the forward end of the furnace.

The floor of the muffle 16, is constructed to support a reciprocable hearth slab 30 which extends from a point adjacent the delivery opening in the muffle to a point exteriorly of the furnace beyond the forward end of the muffle. The slab extends substantially the width of the muffle and is formed with shallow sides 30a, illustrated more clearly in Fig. 2. The receiving end 30b of the slab may be open at its end or closed on three sides as illustrated and functions as a tray, whereas the delivery end is open so that the work may discharge into the chute 19. Where the hearth slab 30 leaves the open end of the muffle a curtain 16a which may be a flame curtain or an adjustable plate, is provided to prevent ingress of unwanted gases and to permit escape of treating gases.

With reference more particularly to Figs. 3 and 4, it is preferred to support the hearth slab 30 on a plurality of rollers firstly to minimize friction and the power factor involved in reciprocating the slab, and secondly to minimize wear between relatively moving surfaces, the latter being very pronounced when the parts are hot. The rollers are constructed of heat resisting metal and in the embodiment illustrated comprise a plurality of groups of round rod pieces 30r arranged on parallel axes extending transversely and at spaced intervals along the muffle. The rollers of each group are confined against undue creep lengthwise along the muffle by means of restricting lugs 30f carried by the hearth slab at either side of the groups of rolls, adequate clearances being provided between co-operating lugs to allow the rolls to revolve as needed. Lateral movement of the rolls may be prevented by providing longitudinal channels or depressions 16d in the floor of the muffle, the side walls of which function as curbings for the individual rollers. If desired, however, the rollers may be a continuous rod and extend from one side wall of the muffle to the other, in which case the side walls of the muffle will function to restrain the rods against undue lateral shifting. In the construction disclosed however, relatively large rollers may be employed because the lower portions are submerged in the channels in the muffle. The floor of the hearth slab is not therefore elevated from the floor of the muffle an excessive distance.

As the hearth slab is reciprocated, the several groups of rollers revolve forwardly and reversely and support the slab throughout its length in substantially frictionless manner.

The provision of groups of rollers or rods between the hearth slab and muffle constructed and arranged in accordance with this invention embody a floating characteristic in that they freely permit either the hearth or muffle to elongate and contract in response to temperature changes and take up new positions accordingly, as well as anti-friction bearings between the normally relatively movable elements.

The side of the outer and exposed end of the hearth slab is provided with fixed pairs of outwardly projecting flanges 30c and 30d disposed at either side of a ball ended lever 31. For aligning purposes and wear compensation adjustable wedges 31a are inserted between the flange 30c and the ball end of the lever 31. Screws 31b are provided to lock the wedges in adjusted position. The lever 31 may, if desired, be constructed as a yoke to straddle both sides of the hearth slab and is pivoted as at 32, to bearing blocks 33 securely mounted to a cross bar 34. The bar 34 forms part of an auxiliary stand 35 that houses power means for imparting oscillatory movement to the lever 31. Lever 31 is provided with an extension 36 that is urged in one direction about the pivot 32, by an adjustable compression spring 37 and in the opposite direction by a hammer cam 38. The spring 37 is mounted upon a pull rod 39 whose effective length is made adjustable by a wing nut 40. The cam 38 is mounted upon the driven shaft 41 of a power transmission, here indicated as a variable speed transmission 42, and is formed with an ascending portion 38a and an abrupt descending portion 38b. As the cam is revolved counterclockwise, in Fig. 1, the lever 36 is caused to move slowly to the left and quickly to the right, at the frequency at which the cam is driven. These movements are transmitted to the hearth slab 30 through the intermediary of lever 31. In consequence the hearth slab is caused to move quickly forward into the muffle and slowly out of the muffle. The forward motion of the slab is brought to an abrupt stop by means of a bumper 50, fixedly carried by the slab, engaging a pad 51 mounted to a spring tensioned bumper block 52. The block 52 is slidably mounted upon the top of the auxiliary stand 35 and held against lateral movement by screws 53 operating in slots 54 formed in flanges at its base. The forward end of the abutment block 52 is provided with a screw threaded extension 55. Jam nuts 56 are positioned on the screw at either side of an angle bracket 58 and opposed springs 57, operating between the jam nuts and the angle bracket, tend normally to constrain the abutment block against movement, but operate to absorb the shock when the slab bumper 50 strikes.

The machine operates as follows: the furnace is brought up to the heat required and the workpieces to be treated are placed in a chute-like tray 60 mounted above the leading end 30b of the hearth slab. The power transmission 42 is set in operation and through the linkages and connections mentioned, the hearth slab is caused to reciprocate within the stationary muffle 16. As the workpieces drop from the tray 60 upon the reciprocating hearth, the forward motion of the latter generates sufficient motion in the workpieces as to cause them to start forward also. However, when the forward motion of the hearth is abruptly stopped by the bumper striking the cushion 51, the inertia of the workpieces causes them to slide a short distance further relative to the hearth. On the relatively slow rearward movement of the slab the workpieces are carried bodily therewith and at the end of the next forward movement they are again jolted forward. In this way the work is advanced step-by-step through the heated muffle until they are caused to slide forward off the delivery end of the slab into the delivery chute and quench medium. The rate of advance of the work along the 75 hearth slab may be varied by regulating the

length of the stroke of the slab and the force with which it strikes the bumper 51, the speed of rotation of the hammer cam, and the tension of the compression spring 37. By properly coordinating these adjustments with the unit mass of the workpieces, the latter may be caused to move along the hearth at the rate best suited to the character of the heat treating process to be carried out. And inasmuch as only the floor of the muffle is actuated, the smaller mass may be stopped more readily, with less wear and destruction, than is occasioned with other designs in which the entire muffle is reciprocated.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claim.

Having thus revealed this invention, we claim as new and desire to secure the following combinations and elements, or equivalents thereof, by Letters Patent of the United States:

In combination, a heat treating furnace having an elongated heating chamber defined by connected upper, lower and end walls, said chamber having an entrance opening in one of the end walls thereof and an exit opening in the lower wall at the end of the chamber remote from the entrance opening, a relatively stationary tubular muffle within the heating chamber of the furnace adapted to surround the work to be treated and to exclude the furnace combustion gases of the chamber from the work, said muffle having its open end portion extending through said entrance opening and a contiguous tubular portion at its other end projecting downwardly through the said exit opening in the lower wall of the heating chamber and providing an exit for the work, means for conducting work to be heat
